UNITED STATES PATENT OFFICE.

JOHN REICHERT, OF RACINE, WISCONSIN.

BRIDLE-BIT.

No. 873,604.

Specification of Letters Patent.

Patented Dec. 10, 1907.

Application filed February 12, 1907. Serial No. 356,992.

To all whom it may concern:

Be it known that I, JOHN REICHERT, a citizen of the United States, residing at Racine, county of Racine, State of Wisconsin, have 5 invented certain new and useful Improvements in Bridle-Bits; and I do hereby declare the following to be a full, clear, and exact description of the invention, such as will enable others skilled in the art to which it appertains

10 to make and use the same.

This invention relates to certain improvements in bridle bits; and the objects and nature of my invention will be readily understood by those skilled in the art in the light of 15 the following explanation of what I now consider my preferred embodiment shown in the accompanying drawings, from among other structures within the spirit and scope of my invention.

20 An object of the invention is to provide certain improvements in and relating to the general type of bridle bit disclosed by U. S. Patent No. 422,529, issued to B. M. Johnson and me on March 4, 1890, whereby certain 25 advantages will be attained in bits of this type.

A further object of the invention is to provide certain improvements in details of construction and in combinations and arrangements of parts for the production of a comparatively simple, durable and highly efficient bit.

30 My invention consists in certain novel features in construction and in combinations or arrangements of parts as more fully and particularly set forth hereinafter.

Referring to the accompanying drawings;—Figure 1, is a perspective view showing the bit applied to the animal. Fig. 2, is an end 40 view. Fig. 3, is a top plan view, the parts being shown in normal driving positions as an "easy bit", a portion of one cheek piece being broken away. Fig. 4, is a top plan view showing the positions of the parts when 45 the pull on the reins has been increased beyond the ordinary guiding or driving pull, to apply the "harsh bit". Fig. 5, is a detail vertical section on the line 5—5, Fig. 3. Fig. 6, is a perspective view of a portion of the bit, 50 looking at the inner side of a cheek piece and the lever passing therethrough, the parts being shown in normal position.

The bit shown comprises the mouth or bit bar 1; the enlarged or ring-like cheek pieces 55 2, at their front edges pivotally joined to the bit bar ends; and the short cam or rein

receiving levers 3, pivotally joined to the bit bar and passing through and controlling the cheek pieces. The bit bar 1, is usually bowed and formed at its extremities with 60 vertical eyes 10, and at the central portion of its rear edge can be formed with a flange or enlargement 11, at its opposite end portions formed with the vertical eyes or perforations 12.

65 Each cheek piece is, in the specific example illustrated, in the form of a comparatively large ring extending rearwardly from the bit bar end. At its front each ring passes loosely and vertically through an end eye 10, of the bit bar, and is formed with shoulders 20, above and below eye 10, to hold the cheek piece in proper position with respect to said bit bar and yet permit said cheek pieces to swing in said eyes 10, toward 70 and from the animal's cheeks. Each cheek piece extends rearwardly from the bit bar a distance equal to the diameter of the cheek piece, and has a horizontal or diametrical slideway extending rearwardly from the bit 75 bar eye and formed by the parallel spaced horizontal diametrical bars 21, merging into and extending rearwardly from the shoulders 20, and at their rear ends merging into the front wall or bar of the rein receiving eye 80 or loop 22, located at the rear end of the cheek piece. The levers 3, extend through said slideways of the cheek pieces and fit loosely between the horizontal bars 21.

85 Each lever 3, is preferably curved or bowed 90 longitudinally and at its inner end formed with a closed eye 30, loosely passing through one of the intermediate eyes 12, of the bit bar. Each lever 3, is formed in one piece with a vertically disposed rein or line loop or 95 eye 32, at its outer end forming an outward continuation of the lever and arranged outwardly beyond the cheek piece through which the lever passes with the outer vertical bar of the loop arranged a distance outwardly 100 beyond the cheek piece. The lever, at the rear face of its outer end and just in front of the loop 32 can be, and preferably is formed with a double inclined cam face or rounded 105 protuberance or boss 33.

110 Each cheek piece intermediate the distance between the loop 22 and the bit bar eye 10, is provided with a vertical cross bar 23 extending between and preferably formed integral with the two horizontal bars 21, and this vertical cross bar 23 is preferably offset outwardly. This cross bar is arranged ap-

proximately in the line of the vertical diameter of the cheek piece and forms a stop limiting the independent rearward movement of the lever in the cheek piece, being so arranged and located with respect to the lever that when the cheek pieces and the levers are in their normal positions to form an "easy bit", the levers will approximately engage said cross bars, with the cross bars or 5 the rollers thereon resting against the rear or outer faces of the double cam inclines at the outer ends of the levers, so that more than ordinary rearward pull on the outer ends of the levers will cause said cam faces 10 to quickly and forcibly press the cheek pieces inwardly. The arrangement however, is such that said cams form a depression in which said cross bars of the cheek pieces rest requiring a hard or more than 15 mere guiding pull on the reins to throw the cheek pieces inwardly to grip the cheeks of the animal and thus constitute a "harsh bit". The cross bars of the cheek pieces normally rest between the highest portions 20 of said cams and the rein loops of the levers so that the ordinary driving pull on the reins for guiding the animal will not cause the levers to throw the cheek pieces inwardly with sufficient pressure against the animal's 25 cheeks to form the "harsh bit", but when the reins are subjected to a hard pull, the cross bars riding up on said cams will throw the cheek pieces inwardly very quickly and forcibly by a comparatively slight rearward 30 movement of the levers.

I preferably mount a vertically disposed anti-friction roller 25, on each cross bar to form a rolling lever engaging surface and to increase the throw of each cheek piece. I 40 offset the cross bars to prevent rubbing engagement thereof with the cheeks of the animal should the rollers not be employed, and where the rollers are employed, to prevent engagement thereof with the cheek of 45 the animal, although I do not wish to limit all features of my invention to the offset cross bar nor to the employment of the rollers but from a specific standpoint advantages are attained by the employment of both of 50 these features.

In bits of the general type of my present invention, as hereto employed, the cheek pieces are swung inwardly to form the "harsh bit" by engagement of the levers with the 55 rear bars of the front rein loops of the cheek pieces, thereby permitting extensive independent movement of the levers in the cheek pieces and causing the cheek pieces to swing in such a distance and at such a sharp angle 60 as to injuriously engage the gums of the animal.

It is an object of my present invention, to so arrange the parts that the cheek pieces will extend a maximum distance rearwardly 65 to forcibly engage the cheeks or lower jaw of

the animal which contain the sensitive nerves so that the animal can be controlled by pressure on these nerve containing cheeks, without injuriously engaging the gums. It is with this end in view, among 70 others, that I couple the extreme front portions of the cheek pieces to the bit bar ends, and arrange the lever engaging cross bars of the cheek pieces intermediate the lengths of the bars 21, so that the cheek pieces will extend 75 rearwardly a considerable distance beyond the cross bars, whereby the independent movement of the levers in the cheek pieces will be very slight, and preferably so 80 form the levers that comparatively extensive and forcible inward movement of the cheek pieces can be attained by comparatively slight rearward movement of the levers.

I also attain material advantages by extending or continuing the levers outwardly a 85 distance beyond the cheek pieces in the form of rein loops rigid with the levers, whereby I attain increased leverage on the cheek pieces and the reins are held a distance outwardly 90 from the cheek pieces.

The short levers 3, are pivotally joined to the bit bar at separated points on opposite sides of the center of the bit bar, and the central portion of the bit bar between the perforations 12, is imperforate to prevent slobbering. I find that an open longitudinal loop at the rear of the central portion of the bit bar causes the animal to slobber whether the loop be formed on the bar or by the inner crossed ends of the levers.

I also so arrange my levers and cheek pieces that the outward swing of either cheek piece is limited, for instance, against swing outwardly beyond the position shown by Fig. 3. This is of advantage as it prevents 105 the bit being drawn through the animal's mouth by excessive pull on one rein. In my device, the short levers curve rearwardly and outwardly to bring the rigid rein loops 32, at the outer faces of the intermediate portions 110 of the cheek pieces, thereby forming effective stops against outward swing of said cheek pieces. Also I prefer to extend the slideway 115 in each cheek piece for the lever to the front of the piece so that the lower bars of the slide-ways uphold the levers and will engage the rigid loops thereof.

In bits of this type heretofore employed, the loose rein rings of the levers, in connection with the formation and arrangement of 120 the cheek pieces, permitted such outward swing of the cheek pieces that under excessive pull on one rein, the bit could be drawn through the animal's mouth, the opposite rein being loose and permitting the adjacent 125 cheek piece to swing out and pass edgewise into the animal's mouth.

Each cheek piece is preferably formed in one piece with a top loop 26, for the cheek strap, and with the large bottom opening 27 130

through which the doubled reins can pass and from which they can hang during hitching and unhitching, and when the bridle is hung up.

5 The rein loops 22, of the cheek pieces are adapted to receive the reins when the bit is to be used solely as an "easy bit". While the cam faces 33, constitute a feature of my present invention, yet I do not wish to limit 10 all features of my invention, to employment therewith.

It is evident that various modifications and variations might be resorted to without departing from the spirit and scope of my 15 invention, and hence I do not wish to limit myself to the exact construction shown.

Having thus described my invention what I claim is;

1. A bit comprising a bit bar at the central 20 portion of its length having a rear flange with vertical end perforations, swinging cheek pieces extending rearwardly from the ends of the bit bar and at their front portions pivotally confined thereto, outwardly extending 25 levers passing through said cheek pieces and at their inner ends having eyes confined in said perforations, each lever having a rein loop rigid therewith and forming an outward continuation thereof beyond the cheek piece, 30 said cheek pieces having lever stops limiting the rearward independent swing of the levers in the cheek pieces.

2. A bit comprising a bit bar, rearwardly extending swinging cheek pieces at their 35 front portions pivotally joined to the ends of the bit bar, levers at their inner ends pivotally joined to intermediate portions of the bit bar and extending outwardly and loosely through the cheek pieces, each lever having 40 a rein loop beyond its cheek piece, each cheek piece formed with a lever slideway and with an offset lever engaging stop provided with a roller and arranged intermediate the front and rear extremities of the cheek piece.

45 3. A bit comprising a mouth bar, swinging cheek pieces pivotally joined to and extending rearwardly from the mouth bar, and levers pivotally joined to the intermediate portion of the mouth bar and extending outwardly and loosely through the cheek pieces 50 and at their outer ends adapted to receive the reins, each cheek piece formed with a lever stop, the outer portion of the rear edge of each lever being formed with a depression 55 to receive said stop.

4. A bit comprising a mouth bar, swinging cheek pieces pivotally joined to and extending rearwardly from the mouth bar, and levers pivotally joined to the intermediate portion 60 of the mouth bar and extending outwardly and loosely through the cheek pieces and at their outer ends adapted to receive the reins, each cheek piece being formed with an intermediate lever stop bar, each lever at 65 its outer portion having a cam incline, said

stop bars adapted to rest behind said inclines when the parts are in their normal positions.

5. A bit comprising a mouth bar, cheek pieces extending rearwardly from and pivotally joined to the ends of said mouth bar, 70 each cheek piece formed with a rearwardly extending slideway and with an intermediate offset vertical cross bar, and levers pivotally joined to the mouth bar extending outwardly through said slideways and at their outer 75 ends adapted to receive the reins, said levers adapted to engage said offset bars to press the cheek pieces inwardly.

6. A bit comprising a bit bar, swinging cheek pieces extending rearwardly from and 80 pivotally joined to the ends of the bit bar, each cheek piece formed with a rearwardly extending slideway and with a vertical stop bar provided with an anti-friction roller mounted thereon, and oppositely extending 85 levers pivoted to the mouth bar and extending outwardly loosely through said slideways and at their outer ends adapted to receive the reins.

7. A bit comprising a bit bar, ring-like 90 swinging cheek pieces pivotally joined to and extending rearwardly from the ends of the bit bar, and each having an outwardly offset vertical cross bar and an anti-friction roller mounted thereon, and the levers pivotally 95 joined to the bit bar and extending outwardly through said cheek pieces and at their outer ends formed to receive the reins.

8. A bit comprising a bit bar, rearwardly extending swingable cheek pieces at their 100 front extremities pivotally joined to the bar ends, each cheek piece formed with a rein loop at its rear end and with substantially parallel spaced guide bars from the front wall of said loop to the front wall of 105 the cheek piece and with a stop bridging the space between said bars and arranged about centrally between the front and rear edges of the cheek piece and intermediate the distance between the front wall of said loop and the front edge of the cheek piece, and rein levers spaced apart and at their inner ends pivotally joined to opposite portions of the central part of said bit bar, said levers extending outwardly between said guide bars 110 115 and in front of said stops and at their outer ends formed with rigid rein loops forming enlarged outward extensions of said levers, substantially as described.

9. A bridle bit comprising a bit bar, rearwardly extending swingable cheek pieces at their front portions pivotally joined to the bar ends and each formed with a longitudinal opening therethrough constituting a lever guideway and with a lever stop arranged 120 about centrally between the front and rear extremities of the cheek piece and forming the rear wall of the guide way, and a pair of rein levers having their inner ends spaced and pivotally joined to the bit bar, 125 130

each lever being joined to the bit bar between the center and an end thereof and from thence extending outwardly and rearwardly through the guide way of the adjacent cheek piece, and outwardly beyond said cheek piece provided with an enlarged rein loop of greater length vertically than the width of said guideway, whereby said levers when in their normal forward positions engage said stops with said rein loops engaging the cheek pieces and maintaining said cheek pieces in their normal rearwardly extending positions and against outward movement, substantially as described.

15 10. A bridle bit comprising a bit bar, rearwardly extending cheek pieces at their front portions pivotally joined to the bar ends and each formed with a rearwardly extending guideway and with a lever stop, and 20 short spaced rein levers at their inner ends pivotally joined to intermediate portions of the bit bar and extending outwardly and rearwardly through the cheek piece guideways, and each having a curved rear edge 25 normally engaging the lever stop of its cheek piece and formed with a rigid enlarged rein loop forming an outward continuation of the

lever and engaging the cheek piece against outward swing thereof.

11. A bridle bit comprising a bit bar, 30 swingable cheek pieces pivotally joined to and extending rearwardly from the bit bar ends and each formed with a guideway there-through having a lever stop, and a pair of short rein levers at their inner ends pivotally joined to intermediate portions of the bit bar, each lever extending outwardly and rearwardly from its inner end through the guideway of the adjacent cheek piece and in front of the stop thereof; and outwardly beyond the cheek piece formed with a rigid enlarged rein loop of greater length than the width of the guideway, said rigid rein loops engaging said cheek pieces and forming stops against the outward swing of said cheek 45 pieces beyond their normal rearwardly extending positions.

In testimony whereof I affix my signature, in presence of two witnesses.

JOHN REICHERT.
